UNITED STATES PATENT OFFICE.

SOLOMON B. MYERS, OF PITTSBURGH, PENNSYLVANIA, ASSIGNOR TO AMERICAN CEMENT TILE MANUFACTURING COMPANY, OF PITTSBURGH, PENNSYLVANIA, A CORPORATION OF PENNSYLVANIA.

ROOFING TILE.

Application filed October 25, 1922. Serial No. 596,791.

To all whom it may concern:

Be it known that I, SOLOMON B. MYERS, a resident of Pittsburgh, Allegheny County, Pennsylvania, have invented a new and useful Improvement in Roofing Tiles, of which the following is a full, clear, and exact description.

The present invention relates to roofing tiles, and more particularly to roofing tiles having translucent panes, such as glass, set therein. In the roofing tile herein described, the pane is set so as to make a very efficient waterproof joint at the edge where most leakage has been experienced, but at the same time to permit the removal and replacement of the pane, if broken. The tile is also arranged so that any moisture, such as water of condensation, is caught by a gutter and conducted to the surface of the roof.

In the drawings forming part of this specification:

Figure 1 is a plan view of a roofing tile embodying my invention;

Figure 2 is a vertical section on an enlarged scale along the line II—II of Figure 1;

Figure 3 is a vertical section along the line III—III of Figure 1; and

Figures 4 and 5 are enlarged detail sections through the tile at its upper and lower edges, respectively, along the line IV—IV and V—V of Figure 1.

As shown in the illustrated embodiment of the invention, the tile comprises a tile frame 1, of cement or other tile material, and a translucent pane 2 of glass or similar material. The framework or body 1 of the tile is made in the usual form, having at one edge the rib 3 and at the other edge the overlapping flange 4 which cooperate with tiles placed on each side to form the overlapping joints. The upper part or cross bar 5 of the frame is plain while the lower part or cross bar 6 is provided with the usual rib 7, which is hollowed at 8 to lap over the joint between the tiles in the next lower row. A seat 9 is formed on the inner edge of the tile frame to receive the glass pane 2. In Figure 1 the pane is shown as removed. In the other figures, the pane is shown in place, but without the cement at its edges.

The upper edge of the seat is provided with an undercut ledge 10, having the pane-

receiving groove 11. The sides and bottom of the seat have plain-faced ledges which allow the glass to be laid down in place and then slid up into the undercut groove 11. This permits the removal of the pane of glass in case it is broken and its replacement by another pane, while at the same time providing the overlapping or undercut ledge 10 at the top of the pane. When the pane is put in place, the edges of the pane are held by an elastic waterproof cement applied similar to the putty on a pane of glass in a window. The liability of leakage of such cemented joint is greatest at the upper edge of the pane where, in accordance with my construction, I have provided the overlapping ledge 10, thereby minimizing the possibility of leakage. Sufficient space is left between the bottom of the ledge 10 and the glass to permit the tilting of the glass when it is inserted and also to receive the waterproofing cement to insure a waterproof joint beneath the ledge.

The seat 9 is provided with a gutter 12, which preferably extends around the entire seat. The gutter 12 terminates in extensions 13, which extend from beneath the pane of glass out on to the upper surface 6 of the tile.

This gutter catches water which may seep in the joint between the tile framework and the pane. The gutter, and particularly the portion of the gutter at the lower edge of the pane, also catches any water of condensation which may form and run down on the under side of the pane, and conducts it away to the outer side of the roof.

While the gutter is shown as extending completely around the seat 9, it may be formed only part way round. This tile provides an overlapping joint of the tile material at the upper edge of the pane, thus making a most secure water tight joint at the place where most trouble has been experienced. The other edges of the pane are not held in undercut grooves, thus permitting the pane to be removed and replaced if broken. The gutter which is formed in the pane-receiving seat of the tile collects and conducts away to the outside of the roof any moisture which would otherwise drop.

While the preferred embodiment of the invention has been specifically illustrated and described, it is to be understood that

the invention is not limited to its illustrated embodiment, but may be otherwise embodied within the scope of the following claims.

I claim:

5. 1. A roofing tile comprising a tile frame and a translucent pane seated therein, the tile frame having a moisture-conducting gutter in the pane-receiving seat thereof beneath the edge of the pane and extending 10 to the outer surface of the tile beyond the lower edge of the pane, substantially as described.
15. 2. A roofing tile comprising a tile frame and a translucent pane seated therein, the tile frame having a pane-receiving seat formed with a gutter in its upper face beneath the edge of the pane, said gutter being substantially co-extensive with said seat and extending to the outer surface of the tile beyond 20 the lower edge of the pane, substantially as described.
25. 3. A roofing tile comprising a tile frame and a translucent pane removably seated therein, the tile frame having formed in the pane-receiving seat thereof beneath the edge of the pane a moisture-conducting gutter extending to the outer surface of the tile, said frame also having an undercut ledge for receiving the upper edge of the pane, substantially as described.
30. 4. A roofing tile comprising a tile frame having a pane seated therein and having a moisture conducting gutter formed in the pane-receiving seat thereof beneath each

longitudinal side edge of the pane, said 35 gutters being substantially co-extensive in length with the pane and each having an extension connecting its lower end with the outer surface of the tile, substantially as described.

40 5. A roofing tile comprising a tile frame and a translucent pane removably seated therein, the upper edge of the pane-receiving seat of said frame being provided with an undercut ledge overlapping the upper edge 45 of the pane, the sides and bottom of said seat having plain-faced ledges which permit the pane to be laid down in place and then slid up into the groove beneath said undercut ledge, substantially as described.

50 6. A roofing tile comprising a tile frame and a translucent pane removably seated therein, the upper edge of the pane-receiving seat of said frame being provided with an undercut ledge overlapping the upper edge 55 of the pane, the sides and bottom of said seat having plain-faced ledges which permit the pane to be laid down in place and then slid up into the groove beneath said undercut ledge, said undercut ledge being 60 spaced from the surface of the pane to permit the reception of waterproofing cement to form a waterproof joint, substantially as described.

65 In testimony whereof I have hereunto set my hand.

SOLOMON B. MYERS.
